HIGH ELEVATION MASK

Arthur H. Bulbulian, Rochester, Minn.

Application July 19, 1943, Serial No. 495,373

2 Claims. (Cl. 128—141)

1

My invention relates to high elevation masks for controlling delivery of oxygen to aviators, particularly where said oxygen is delivered under pressure, and has for its object to provide a mask improvement of distinctive form which can be worn comfortably and will effect perfect sealing against the face of the wearer, even in cases where the face has extremes of hollows and bony contours.

Conditions of aviation in modern warfare have brought about the flying of airplanes to ever greater and greater heights, so that at the present time it is not uncommon for airplanes to move over enemy country and even to be engaged in combat at heights up to or in excess of eight miles. It has been found that the occupants of airplanes at the upper limits are maintained with less shock and injury to health when pure oxygen is delivered to them at pressures considerably higher than that of the surrounding air pressure. A problem has been encountered both in maintaining such pressures and in preventing waste of costly oxygen in and from the breathing chamber formed within the mask against the face of the aviator by reason of a tendency for leakage to take place about the margins of the mask.

While heretofore there has been accomplished sufficient fit of the face-contacting portions of the mask body with the face to prevent too much leakage when there is little pressure within the breathing chamber, and to avoid serious discomfort, these means have not been effective to prevent waste of oxygen when it is delivered to the breathing chamber at pressures substantially greater than the surrounding atmospheric pressures. In those instances where the face-contacting portions of the mask have comprised rolled over margins or expanded pneumatic tube margins the area of actual contact with the face has been small and there is opportunity for the pressure within the breathing chamber to force the gas under such rolled or curved contacting portions to produce a lifting thereof and consequent escape and waste of the pressure gas.

I have discovered that if face-contacting marginal portions of a mask are formed to have a general fit over the nose, cheeks and chin of the wearer, with an inner plate having its face-contacting portion of substantial width and at the same time said portions at their inner margins where they bound the rear part of the breathing chamber are made integral with but spaced from an inner portion of the main part of the mask, the positive pressure within the mask either from

5 feed of oxygen or from exhalation, will be applied back of this free flap-like inner margin and will cause it to fit itself in sealing relation upon the contacted parts of the face so that substantially no leakage can take place. Such a mask structure may be formed according to the process disclosed in my copending application, Serial No. 495,968, now abandoned.

It is a principal object of my invention, therefore, to provide a mask having a space therein for a breathing chamber open to the mouth and nose when the mask is applied to the face, wherein the contacting portions of said mask comprise a plate of flexible material, such as rubber, surrounding the opening into the breathing chamber formed when the mask is worn, shaped and proportioned to provide a unitary continuous face-contacting surface and embodying relatively thin outer portions continuous with the main body of the mask and an inner portion integral with said outer portion yet separated and slightly spaced from the interior of the mask body.

It is a further object of my invention to have 25 the inner separated portion of said contacting plate connected with the nose-receiving portion of the mask so that it shall have a free part extending around the inner part of the nose as worn.

30 It is a further object of my invention to provide such inner flap-like member integral at its outer edge with, but separated at its inner edge from, the main mask body with a portion at the chin, which, in conjunction with the outer 35 portions of the face-contacting member will form a chin rest which aids in keeping the mask in position on the face and also prevents condensate within the mask from getting between the face and the contacted parts of the mask.

It is a further object of my invention to provide a face-contacting plate having a continuous, unitary, face-contacting surface, and which plate is in effect hinged though integrally connected to the body of the mask in a line between its 45 edges so as to provide an inner flat portion separated from and disposed at an acute angle to said mask body.

I have, in the specification appended hereto, pointed out in detail the advantages and the mode 50 of operation of my mask structure, and the novel features embodied therein by which the aforesaid advantageous results are obtained will be particularly pointed out in the claims.

In the drawings illustrating an application of my invention in one of its forms:

2

Fig. 1 is a plan view of my mask viewed from the open or face-contacting side.

Fig. 2 is a sectional view through the mask taken on the line 2—2 of Fig. 1.

Fig. 3 is a sectional detail view of a fragmentary portion of one side of the mask taken on the line 3—3 of Fig. 1.

Fig. 4 is a top plan view of my mask embodying the features of my invention.

Fig. 5 is a side elevation view of my mask.

Fig. 6 is a fragmentary view taken on the line 6—6 of Fig. 1.

As illustrated, my mask development comprises a main mask body 10 which with parts hereinafter referred to provides a breathing chamber 11 sealed to the face of the aviator. From this breathing chamber opens a microphone turret 12, an exhaling valve 13, and inhalation openings 14 and 15. An extension 16 forms an exhaling chamber 17 which covers the exhaling valve 18, and from the exhaling chamber 17 lead wide flat exhaling tubes 18 and 19 which furnish very short downwardly extended exhalation passages to atmosphere.

The openings 14 and 15 lead through buried tubes which lie under the exhalation tubes 18 and 19 to openings 20 in an inhalation tube 21. The body 10 provides a top extension 22 which, in conjunction with the particular face-sealing member which forms an essential part of my invention, provides a nose-contacting portion of the mask. The entire arrangement in connection with that face-sealing member provides an unusually effective mask structure which can be worn with exceptional comfort while at the same time giving a highly efficient and dependable seal against escape of gas from the breathing chamber.

At the outer limits of the mask body 10, as indicated at 23, there is united integrally (by means of my aforesaid process) and along a line intermediate its limiting edges a face-contacting plate 24. This union in effect hinges the plate 24 to the mask body 10. This plate has a continuous unbroken unitary face-contacting surface 25 and is integrally secured to the body part 10 at 23 so that said face-contacting surface 25 extends at an acute angle to the body portion with which it is united. The plate 24 is shaped and proportioned to have its surface 25 conform to the average face contours of a wearer, and said plate comprises an outer part 26 and an inner part 27 which is separated from the body 10 by an acute angle indicated at 28 in Figs. 2, 3, and 6. This produces as a part of the face-contacting plate 24 and its inner surface 25 a free flap 27 which is angularly spaced from the body 10 as indicated at 29, and this flap is positioned to engage the bony parts and hollows on the sides of the cheeks and also on the sides of the nose, see Fig. 2.

This face-contacting arrangement differs very sharply from rolled-over edges of the body portion and pneumatic tube arrangements at the margins of a mask. It provides a wide continuous face-contacting surface with an inner flap member separated from the mask body and subject to the pressure within the mask and yet one which is integrally united with the body of the mask. It gives a face-contacting plate which, in effect, is hinged along a line intermediate its edges, an arrangement which very definitely secures a sealing fit over all parts of the face of the wearer.

The plate 24, as best shown in Fig. 1, limits with its inner edges 30 the opening 31 into the

breathing chamber 11. This plate has a lower part, indicated at 32, Figs. 1 and 2, in which the inner portion 27 is considerably thickened as shown at 33 and, over the bottom part of the mask body and the breathing tubes formed therein, provides a curved rest 34 for the chin of the wearer. At the same time the part thereof indicated at 35 in Fig. 2, forms a guard against forward thrust of the aviator's chin over the exhalation valve 13, and a barrier or dam against condensate which will form in the breathing chamber getting under the chin and along the face of the wearer, a matter which has proved highly uncomfortable and has serious other disadvantages.

The strapping arrangements shown are exceedingly effective for this type of mask in which a strap 36 overlies the main body of the mask being secured thereto by rivets 37 and 38. Through buckles 39 and 40 attached to straps on a head harness or helmet, not shown, the mask may be drawn firmly upon the face of the wearer. The aforesaid straps, as connected with a head harness, may go either over the upper part of the back of the head or neck. A second strap 41, Fig. 4, is connected by a loop 42 with the first strap and has a buckle 43 which may connect with a strap on the helmet or head harness for suspending the mask in a convenient position to be quickly applied to the face by making the one connection with the buckle 40.

The advantages of my invention have been very fully pointed out in the foregoing specification. The primary advantage of essential importance is that the mask structure provides a face-contacting member which at the same time is exceptionally comfortable when worn and effects a practically complete sealing of the breathing chamber against the face of a wearer, accommodating itself to the many different types of hollows and projections due to differences in the bony structure of the faces of different wearers. Thus a single size of mask may be effectively employed in general upon faces of entire groups.

A further great advantage comes from the ease and certainty with which the mask may be applied to the face of a wearer and correctly positioned for use, due in large part to the continuous shaped inner surface of the face-contacting plate and the chin-receiving part or chin rest related to the nose-receiving part.

I claim:

1. A high elevation mask, comprising a body portion adapted to enclose a breathing chamber as worn, a marginal face-contacting plate of such width as to contact large areas about the upper part of the nose, the sides of the cheeks and under the chin of the wearer, said plate being connected substantially along its center with the edge of said body portion and having the inwardly extended part thereof thin and flexible and connected at an acute angle to bring it close to the mask body, the outer portion of said plate forming in effect a continuation of said mask body, the said plate being adapted to rock on its line of union with the mask body to fit closely the large areas over the sides of the cheeks and under the chin, a gas inlet part having a thickened connection to the body part at the center of the mask, and the under chin portion of said plate being united to the mask body and to the inlet part in a thickened mass forming a stress-resisting chin rest.
2. A high elevation mask, comprising a body

portion adapted to enclose a breathing chamber as worn, a marginal face-contacting plate of such width as to contact large areas about the upper part of the nose, the sides of the cheeks, and under the chin of the wearer, the inner edges of said plate forming a contracted relatively small opening into the breathing chamber, an air inlet tube and branches therefrom anchored to the body portion of the mask across the lower central part thereof, said plate being connected substantially along its center with the edge of said body portion and having the inwardly extended part thereof thin and flexible and connected at an acute angle to bring it close to the mask body as worn, the under chin portion of said plate being united to the mask body and to the inlet part in a thickened mass forming a stress-resisting chin rest.
